(57) **CLAIM**

The ornamental design for a boresnake storage box, as shown and described.

DESCRIPTION

FIG. 1 is a front, top perspective view of a boresnake storage box showing my new design;

FIG. 2 is a front, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines shown in the figures are for the purpose of illustrating portions of the boresnake storage box, which form no parts of the claimed design.

1 Claim, 5 Drawing Sheets
